UNITED STATES PATENT OFFICE

2,618,036

SHOE HAVING ADJUSTABLE FASTENER

Noel Statham, New Canaan, Conn.

Application May 27, 1950, Serial No. 164,821

2 Claims. (Cl. 24—206)

1

My present invention relates to improvements in shoes, more especially of the type having a releasable securing strap across the instep or top of the foot. When a shoe of this type has been drawn over the foot, it requires but a single operation of fastening the strap to the side of the shoe. Heretofore it has not been found practicable to provide an adjustable fastener for the end portion of the strap. It is the object of this invention to overcome this drawback by employing a fastener of a type previously invented by me and which I have adapted to its present use.

Further objects of my invention and the advantages thereof will be apparent as the description proceeds. The invention will be best understood by reference to the following detailed description taken with the annexed drawings in which

Fig. 1 is a plan view of a shoe containing a preferred embodiment;

Fig. 2 is a side view of the same, showing one fastener element in place;

Fig. 3 is an enlarged view in section along line 3—3 of Fig. 1;

Fig. 4 is a view in section along line 4—4 of Fig. 3;

Fig. 5 is a view in section along line 5—5 of Fig. 3;

Fig. 6 is a view in isometric perspective of a securing plate forming a part of the attaching means;

Fig. 7 is a view similar to Fig. 1 but showing a modification;

Fig. 8 is a side view of the shoe as seen in Fig. 7;

Fig. 9 is a view of a part of the shoe showing a slot cut in the outer surface to receive one of the attaching elements;

Fig. 10 is a view in section along line 10—10 of Fig. 9;

Fig. 11 is a view in section along line 11—11 of Fig. 8;

Fig. 12 is a view in section along line 12—12 of Fig. 7;

Fig. 13 is a view along line 13—13 of Fig. 7;

Fig. 14 is a view in longitudinal section showing a further modification; and

Fig. 15 is a view in cross-section of a further form of track in place on the shoe.

In Fig. 1, the shoe, denoted generally by 1, is of the type having a strap 2 over the instep which is releasably secured to a side portion 3 of the shoe. The top 4 of the shoe terminates in the usual tongue 5.

As seen particularly in Fig. 3, the end por-

tion of strap 2 has attached thereto a slider, denoted generally by A, which engages and is adjustably secured on a track denoted B. Thus the slider is secured to the strap 2 while the track B is secured to the portion 3 of the shoe. The slider A comprises a body portion 7 of generally C-shaped cross-section which, by virtue of this shape, is adapted to be secured to track B by engaging beneath same as shown in Fig. 4. Body portion 7 has upstanding ears 8, 8 which pivotally support a clamp or locking element denoted generally by 9. This element 9 comprises a tab portion 10 and a cam portion 11 and is further provided with trunnions 12 which engage apertures in the ears 8, 8, as best seen in Fig. 4. The material forming said ears is taken from the body portion 7, thereby forming an aperture in said body portion, denoted 13, to enable the cam or locking portion 11 to come in contact with the track B, as in Figs. 12 and 13, or as shown in Fig. 3 to contact a separate locking plate 14, Fig. 6, which is provided with corrugations 15 and is held floatingly in place by a notch 16 on either side, to accommodate the ears 8. The corrugations 15 register with corrugations in the track to be described, whereas the top of the plate 14 is engaged by the cam 11. The use of the plate 14 provides for gripping the track to be described over a plurality of corrugations rather than between a single pair of same, if this plate were not used. (A suitable aperture must be cut in the strap 2 as best seen in Fig. 3.) As shown in Figures 1, 3 and 4, an apertured facing plate 17 is placed over the slider with the tab 10 projecting through the aperture, the plate 17 being secured in place by tabs or fingers 18 which pass through the material of the strap 2 and are bent over in clamping engagement as shown in Fig. 4.

The track B in the form shown in Figs. 2 and 3 consists of a metallic hollow member or shell 20 which encloses a small metallic securing rod or wire 21 which passes through the length of said shell, and is then caused to project therefrom through the material of the side 3 and then to be turned over as indicated at 21a, thus clamping the top end of the shell to the shoe piece 3. Similarly at the lower end the rod 21 is caused to make a U-bend 21b. Preferably the material of the bends 21a and 21b is covered by the shoe lining 22. Shell 20 has corrugations 20' stamped or otherwise formed therein for engagement with either the corrugations of the floating plate 14 or the end of the clamping member 9. The end of the track B adjacent the top of the instep is enlarged as at 23, thus providing a stop for the

Slider which is threaded thereon at the opposite end 24. Alternatively, the shell 20 and the inner rod 21 may be made integral if desired.

Figs. 7, 8, 9, 10, 11 and 12 show a further modification. Here the track B' consists of a fabric strip 25 which by means of stitching 26 and the folds 27 therearound has formed therein a ridge upon which are secured staples 28 at regular intervals, Figs. 8 and 11. The track so formed is attached to the shoe by means of the fabric strip 25, which preferably is secured between the outer layer 29 of the shoe and the lining 30 by parallel rows of stitching, as shown best in Fig. 11. A stop 31 is disposed at the end of the track at the top of the instep, as in the previously described embodiment. The slider A' in this embodiment may comprise a crosspiece 32 (Fig. 13) by virtue of which the end of the strap 2' may be joined. As shown the strap 2' is apertured to receive the crosspiece 32. At the region of the aperture, the strap is turned 180° and the loop thus formed is secured by means of stitching 33. The slider A' is similar in all respects to slider A except that it lacks the outer casing 17. In operation the slider A' is threaded upon the end of the track B' remote from the stop 31 and is secured in adjusted position by bringing the tab 10' downwardly in locking position. Similarly to release the slider the tab is moved in the opposite direction.

In Fig. 14 a track B'' is employed of plastic material having corrugations 34 formed at the outer surface thereof, as shown. This track is secured to the shoe by means of stitching 35. Otherwise the operation and construction of the device is similar to the form shown in Fig. 7.

Similarly, in Fig. 15 a track 36 is employed, formed of a plastic impregnated fabric secured by stitching 37. The plastic tracks of Figs. 14, 15 are further shown in my Patent No. 2,437,765. 40

In use the strap 2' or 2'' is of sufficient length so as to enable the slider to be threaded over the far end of the track B. This threading operation may be done preferably before the shoe is

put on. After the foot has been inserted into the shoe, the end of the strap is then moved downwardly until the strap has been drawn sufficiently tight, whereupon the tab 10 or 10' is brought downwardly into clamping position. Normally, once having brought the slider over the far end of the track, the slider is not thereafter removed from the track but is merely adjusted to any desired point thereon.

I claim:

1. In an adjustable fastening means for a shoe, a securing strap, a track consisting of a continuous strip of material attached to said shoe proper, a slider fixably attached to the strap and adapted to engage beneath said track and being slidable therealong while attached thereto, said slider carrying a clamp operable to fix the slider at a point at will along the track, said track consisting of an elongated metallic hollow member having a rod-like member extending therethrough and each end thereof projecting beyond the ends of said track and bent beneath the surface of the shoe to retain the track in place.

2. The fastening means of claim 1, in which the track has an enlarged end serving as a stop for the slide.

NOEL STATHAM.
